United States Patent Office.

WILLIAM P. BENNETT, OF EAST PEPPERELL, MASSACHUSETTS, ASSIGNOR
TO HIMSELF AND HENRY BLAKE, OF THE SAME PLACE.

Letters Patent No. 70,392, dated November 5, 1867.

IMPROVEMENT IN LAMP-EXTINGUISHERS.

The Schedule referred to in these Letters Patent and making part of the same.

TO ALL PERSONS TO WHOM THESE PRESENTS SHALL COME:

Be it known that I, WILLIAM P. BENNETT, of East Pepperell, in the county of Middlesex, and State of Massachusetts, have invented a new and useful Kerosene-Burner Extinguisher; and do hereby declare the same to be fully described in the following specification, and represented in the accompanying drawings, of which—

Figures 1 and 2 are vertical and transverse sections of a burner provided with my invention, these sections being taken in planes at right angles to each other.

Figure 3 is a top view,

Figure 4 an end view, and

Figure 5 a side view of the wick-tube and its appliances.

The principle of my invention is to be found in the application of two rollers to the wick-tube, so that the said rollers may operate with and be operated by the wick, substantially in the manner as hereinafter explained. Also, in the combination and arrangement of slotted arms with the two rollers and the wick-tube, or with an additional or cap-tube or collar to fit upon the wick-tube, as hereinafter set forth. Also, in the combination, as well as the arrangement, of two air-stops with the rollers and wick-tube, when such rollers are applied to such tube so as to be operated by and with the wick, in manner as hereinafter described.

In the drawings, A denotes the body, B the wick-tube, and C the air-deflector of a common kerosene-lamp burner. D is the wick and E its elevator. Directly over the top of the wick-tube are two rollers, *a a*, whose journals are arranged in the slots *c c c c* of four slotted arms, *b b b b*, disposed with respect to the wick-tube in such manner as to enable the wick, while being elevated above the top of such tube, to pass between the two rollers, and separate them or move them asunder, and cause them to rise upward, in order that when the wick is next depressed, the rollers, by their gravity, may fall and come or approach together again over the top of the wick, so as to extinguish any flame thereon. Each of the arms stands obliquely with respect to the top of the wick-tube, in manner as represented. They may project directly from the wick-tube, or from a tube or collar, *f*, to encompass and fit to the wick-tube. On the tube from which the arms extend I place a collar, *g*, provided with projections or stops *h h*, which, when the rollers fall in their lowest positions, extend alongside of them, and up or nearly up to them, when they are in their highest positions. These guards or stops prevent the wick from becoming inflamed below the rollers, and prevent air from passing below the rollers to the wick, so as to aid in inflaming it below the rollers. Besides this, the guards or stops are advantageous in other respects. By moving the wick vertically by the ordinary wick-elevator or spur-pinion E, fixed on a cross-shaft, we can effect the necessary movements of the rollers, and, as they drop by their gravity over the top of the wick, they will at once extinguish the flame.

I claim the application of the two rollers *a a* to the wick-tube of the burner, so that the said rollers may operate with and be operated by the wick, substantially in manner and for the purpose set forth.

I also claim the combination and arrangement of the slotted arms *b b* with the two rollers *a a*, and the wick-tube, or with an additional tube or collar, *f*, applied to such wick-tube as specified.

I also claim the combination, as well as the arrangement, of the stops or guards *h h* with the rollers *a a* and the wick-tube, applied and arranged together substantially as explained.
